ULTRA HIGH FREQUENCY RADIO
TRANSMITTER

Ronald Springford Hope, London, England, assignor to International Standard Electric Corporation, New York, N. Y., a corporation of Delaware

Application June 7, 1947, Serial No. 753,305
In Great Britain March 15, 1946

Section 1, Public Law 690, August 8, 1946
Patent expires March 15, 1966

10 Claims. (Cl. 250—17)

1

This invention relates to radio transmission systems. More particularly, it relates to transmitting and radiating arrangements suitable for systems operating at very short wavelengths.

It is an object of the invention to provide a compact oscillation-generating and radiating unit employing a slot aerial.

It is a further object of the invention to provide a compact frequency modulated oscillation-generator and radiator unit employing a slot aerial and specially suitable for use in a radio altimeter of the frequency sweep type.

According to the invention there is provided an ultra-high-frequency radio transmitter unit comprising a resonating section of coaxial transmission line having a radiating slot aerial in the outer conductor, said resonating section being closed at each end by a screening header and being excited by a thermionic valve oscillator mounted within the transmission line and header assembly.

The invention further provides, for use in a radio altimeter system of the frequency sweep type, a transmitter unit according to the preceding paragraph in which one transmitted frequency by variation of the capacity between the header and the inner conductor of the said resonating section, the said capacity being formed between fixed condenser vanes on the said inner conductor and condenser vanes on the header rotated by an electric motor within the header.

Other objects and features of the invention will become apparent from the following detailed description of a preferred embodiment of the invention taken in conjunction with the accompanying drawings, in which—

Fig. 1 is an "exploded" perspective view of an 18 cm. wavelength oscillation-generating and radiating unit in accordance with the invention, with certain parts cut away in order better to show the interior construction.

Fig. 2 is a perspective view of the assembled unit illustrated in Fig. 1.

In these drawings a given reference numeral refers to the same part in both figures.

Referring now to Fig. 1, the unit comprises a resonating section of coaxial transmission line having an inner conductor 1 and an outer conductor or shell 2, the outer conductor being substantially one quarter wavelength in diameter and having located thereon a radiating slot aerial 3, only part of which is visible in the figure. This slot is arranged transversely i. e. in a plane perpendicular to the axis of the resonant coaxial line, opposite a voltage mode on the coaxial reso-

2

nator, has a width of the order of one hundredth of a wavelength, and subtends an angle of substantially 90° on the surface of shell 2, the length being thus rather less than one quarter of a wavelength at the operating frequency. The inner conductor 1 is supported within the outer conductor 2 by insulators 4 spaced round a circumference of the shell at 120° intervals. One end of the coaxial line is closed by a metallic header 5 which is adjustably mounted on and galvanically connected to the shell 2 by screw-thread means. Within the header 5 is mounted a small electric motor the shaft of which extends through the face 6 of the header and carries two butterfly condenser vanes 7. The header 5 is mounted within shell 2 at such a distance along the axis of the resonator that the capacity formed between the end of inner conductor 1, which carries two fixed butterfly condenser vanes 7 machined on its end surface, and the header-face 6 with condenser vanes 7 in the reference position, serves to tune the resonator to the reference frequency.

The resonating coaxial section is excited by a valve 9 which is mounted in the assembly with its longitudinal axis colinear with the axis of the resonating section. This valve, of a type already known in the art, is a triode with grid and anode connections brought out by disc seals to annular contacts encircling the glass envelope as shown at 10 and 11, while the cathode heater connections are brought out as the inner and outer conductors 12 and 13 of a coaxial line, the cathode itself being joined to the conductor 12 within the valve. Also within the valve are two small metal probes connected to the cathode and passing through the grid into the anode-grid space, providing feedback whereby sustained oscillations may be set up without any external feedback circuit.

The valve 9 is mounted in the transmitter unit by inserting the anode end of the valve envelope into the recess 14 in the inner conductor until the anode disc seal annulus 11 rests on the shoulder 15, against which it is then clamped by clamping ring 17 which threadably engages with the inner conductor. Thereafter the cathode header 16 is pressed over the remainder of the valve to complete the grid, cathode, and header connections in the following manner.

The cathode header 17 comprises a metal washer 18, ring 19 of mica or other suitable insulating material, a metal spring washer 20, a metal back plate 21, the cathode connector line assembly 22, and clamping ring 23, references 18

to 21 inclusive being rigidly fixed together by insulated screws and nuts not shown on the drawing. Attached to and projecting radially inwardly from the inner rim of washer 18 is a circumferential group of spring leaf contacts 24 which bear on the grid disc seal 19 to make contact therewith. By virtue of the capacity of the condenser formed, by the washer 18, mica ring 19, and washer 20 with backplate 21, the grid is coupled for high frequency voltages to the shell or outer conductor 2 of the coaxial resonating line when the back plate 21 is clamped against the edge of shell 2 by clamping ring 23 which threadably engages with shell 2. Provision for biasing, keying or modulating the grid is given by terminal 25 which is insulatedly mounted on the back plate 21 and is connected to the washer 18 by a lead which is insulated from washer 20. The cathode line assembly 22 comprises a metal cylinder 26, rigidly secured to back plate 21, on the end of which, but insulated therefrom, is a flexible metal cap 27. Secured to the cylinder is a shaped metal member 28 adapted at one end to fit over the cathode end of the valve envelope, but not touching the grid seal, while the other end is contracted to a narrow cylinder in which the valve cathode connector 12 makes sliding contact. Coaxially within this narrow portion of shaped member 28, insulated therefrom, and mounted on the flexible cap 27 is a split spring socket, not shown on the drawing, into which fits the valve heater connector 13. The cathode heater supply is fed to a centre terminal 29 mounted directly on the metal cap 27, and to a terminal 30 insulatedly mounted on the cap but connected to the shaped member 28. The length of cylinder 26 is made such that the heater leads from the flexible cap 27 to the cathode itself are substantially equal to one quarter wavelength long at the operating frequency and behave as quarter wavelength transmission line short circuited at the cap end by the capacity of insulated terminal 30 to the cap 27, thus preventing high frequency power being lost in the cathode heater supply circuits.

High tension supply to the anode is fed to the transmitting unit at terminal 31 which is insulatedly mounted on the shell 2 and is connected to the inner conductor 4 by helical connection 32 which also serves as a protective feed choke.

In order to provide some means, additional to varying the position of header 5, for varying the mean frequency of the oscillating system, a trimming condenser is provided in the form of metal screw 33 which is mounted on shell 2 and projects into the space between the inner and outer conductors of the resonating transmission line section.

The apparatus so far described constitutes a simple embodiment of the invention as applied to a radio altimeter of the frequency sweep type, in which the frequency of the transmitted wave is cyclically varied over a predetermined range, and the altitude indication is derived from the frequency difference between the wave emitted by the transmitter and that contemporaneously received from the transmitter by reflection from the earth. In the present embodiment the required cyclical variation of frequency is provided by the rotation of the butterfly condenser vanes 7 under the control of the small motor already referred to as included within the header 5. No details of the mechanism for rotating the condenser vanes are included in this specification,

since any convenient means such as are already well known in the art may be applied to this purpose.

The radiation from the slot normally gives a beam of large included angle. When the radiation can usefully be restricted to a narrower beam, it is advantageous to add a corner reflector system to the slot aerial system, such reflector comprising two flat metallic reflecting plates arranged symmetrically with respect to the aerial in planes which intersect in a V configuration, the apex of the V being contained in or perpendicular to the transverse plane in which the slot aerial is contained. In extreme cases a second corner reflector system may be added, disposed in space quadrature relative to the first corner reflector, as is done in the case of the present embodiment and illustrated partly in Fig. 1 and more fully in Fig. 2.

Referring now to Fig. 2, this shows an external perspective view of the assembled transmitting and radiating unit of which the main details have already been described.

In this figure references 34 and 35 represent the two metal plates of a corner reflector disposed with the plates in planes which intersect along the axis of the coaxial resonator. The angle between the plates is substantially 90°, but if necessary this angle may be changed a few degrees in either direction to effect adjustment of the beam width. These plates are mounted in shell 2, and in galvanic contact therewith, either by flanges and fixing screws or by welding or by any other convenient means. The length of the plates in the radial direction is such that the distance from the axis of the resonator to the outer edge of the plate is preferably not less than one half wavelength, while the length parallel to the axis of the resonator is preferably not less than one half wavelength. In Fig. 2 the plates 34 and 35 are shown with flanges 36 and 37; these flanges may be used for mounting the assembly, for example in an aperture of the wing of an aircraft, but play on other parts. Corner reflector plate 35 is also shown in Fig. 1, but plate 34 has been omitted in order to simplify the drawing.

Referring again to Fig. 2, a second corner reflector is illustrated using reflecting plates 38 and 39, symmetrically positioned with respect to the ends of the slot aerial and forming a V configuration, the apex of which would lie on a line in the transverse plane containing the slot aerial 3. In order to avoid interfering with easy removal or adjustment of the headers, as for example when changing a valve or altering the distance between the fixed condenser vanes 8 and rotatable vanes 7 for the purpose of changing the frequency sweep, reflecting plates 38 and 39 instead of being mounted on shell 2 are rigidly secured to the other reflector plates 34 and 35 (which are themselves secured to shell 2) and are shaped to fit over the cylindrical shell. This however leaves the possibility of parasitic slot aerials being formed between shell 2 and the reflector plates, and consequent loss of radiation efficiency. To overcome this difficulty, each of the reflector plates 38 and 39 is fitted with a resilient metallic comb 40 the flexible teeth of which bear on shell 2 and effectively short circuit any parasitic slot which might otherwise arise. The angle between the reflector plates is substantially 90°, as in the case of the first described corner reflector, and the plates extend to a distance of at least half a wavelength from the

apex of their V configuration, while the outer edges are bounded by the plates 34 and 35.

It will be understood however that even if the corner reflector composed of plates 34 and 35 is not fitted the corner reflector composed of plates 38 and 40 may still be fitted, in which case it could for example be secured to brackets radiating from shell 2 with an included angle of 90°.

Still referring to Fig. 2, it will be observed that the ends of the slot are slightly enlarged and arcuate in shape, the radius of the arc being about twice the width of the slot at its centre. This shaping of the ends, and the choice of the most suitable length and width, should be governed by the desirability of obtaining a good impedance match between the radiative load and the oscillatory system comprising the valve and the coaxial resonator the effective impedance of which, as viewed by the valve, is determined by the coupling of the radiation load via the slot aerial.

Since the assembly containing the valve is closed at the ends by the two headers it is advisable to make provision for dissipating the heat generated in the valve in the form of cathode heater power, anode losses, and the like. In the present embodiment of the invention this provision takes the form of an aperture in the cathode header through which cooling air may be forced under pressure over the grid and anode seals through a number of short slits in the clamping devices, the heated air being expelled through the slot aerial.

While the invention has been described with reference to an embodiment using a particular type of valve, it is to be understood that other types of valve suitable for the purpose may be employed. For example, a valve may be used in which the feedback probes are connected to the anode instead of to the cathode, or in which no feedback probes are used at all, the feedback being obtained through the normal inter-electrode capacities.

Having now particularly described and ascertained the nature of my said invention and in what manner the same is to be performed, I declare that what I claim is:

1. An ultra high frequency radio transmitter unit comprising a resonant section of a coaxial transmission line, a screening header closing each end of said section, a thermionic valve having at least a cathode, an anode, and a control grid electrode energised from external sources, said anode and grid electrodes having disc seals coupled respectively to the inner and outer conductors of said resonating section at one end, and a transverse slot aerial in said outer conductor arranged parallel to and adjacent the connection between said grid disc seal and said outer conductor.

2. A radio transmitter unit according to claim 1 further comprising at least one probe electrode disposed partly within the cathode-grid space and partly within the grids anode space and connected to one of said valve electrodes other than the grid for feeding back energy in said valve to sustain oscillations therein.

3. A radio transmitter unit according to claim 1, wherein the inner conductor of said resonating section is recessed to receive that part of the envelope of said thermionic valve extending from the anode seal away from the cathode end, and is galvanically coupled to said anode.

4. A radio transmitter unit according to claim

1 wherein the header at the excited end of said resonating section is adapted to receive that part of the envelope of thermionic valve extending from the grid seal in the direction of the cathode, and is adapted to couple said grid to the outer conductor of said resonating section through capacity having negligible reactance at the operating wavelength.

5. A radio transmitter unit according to claim 10 1 wherein the header at the excited end of said resonating section comprises transmission line means for connecting the cathode heater system of said valve to energising terminals mounted on said header, said terminals having between them 15 capacity of negligible reactance at the operating wavelength, the conductors between said terminals and said heater forming in conjunction with said terminal capacity a quarter wave transmission line filter.

20 6. A radio transmitter unit according to claim 1, further comprising a corner reflector system symmetrically positioned about the longitudinal axis of said slot aerial, said corner reflector system comprising two substantially flat metallic 25 plates each radially mounted on said outer conductor and in galvanic contact therewith for substantially the whole length of one edge, the angle included by said plates being of the order of 90°; and the length of said contacting edge being 30 substantially one half wavelength.

7. A radio transmitter according to claim 1, further comprising a corner reflector system symmetrically positioned with respect to the ends of said slot aerial, said corner reflector system comprising 35 two substantially flat metallic plates in planes forming a V configuration with apex line in the transverse plane containing said slot aerial, the angle included by said plates being of the order of 90°, each plate having an edge 40 contiguous to the surface of said outer conductor and being galvanically connected thereto in such manner as to short-circuit any parasitic slots of substantial magnitude.

8. A radio transmitter unit according to claim 45 1 further comprising a first corner reflector system symmetrically positioned about the longitudinal axis of said slot aerial, said corner reflector system comprising two substantially flat metallic plates each radially mounted on said 50 outer conductor and in galvanic contact therewith for substantially the whole length of one edge, the angle included by said plates being of the order of 90°; and the length of said contacting edge being substantially one half wavelength, 55 and a second corner reflector system symmetrically positioned with respect to the ends of said slot aerial, said second corner reflector system comprising two substantially flat metallic plates in planes forming a V configuration with apex line in the transverse plane containing said slot aerial, the angle included between said plates being substantially 90°, each plate having an edge 60 contiguous to the surface of said outer conductor and being galvanically connected thereto to short-circuit any parasitic slots of substantial magnitude, the plates of both said corner reflector systems being galvanically connected together and extending outwardly substantially one half wavelength from the axis of said 65 resonating section of coaxial transmission line.

9. An ultra high frequency radio transmitter unit comprising a resonant section of a coaxial transmission line, a screening header closing each end of said section, a thermionic valve having at least a cathode, an anode, and a control

7
grid electrode energised from external sources, said anode and grid electrodes having disc seals coupled respectively to the inner and outer conductors of said resonating section at one end, and a transverse slot aerial in said outer conductor arranged parallel to and adjacent the connection between said grid disc seal and said outer conductor and capacitive means between the header remote from the excited end of said resonating section and the inner conductor of 10 said resonating section for tuning the section.

10. A radio altimeter system of the frequency sweep type comprising a radio transmitter unit according to claim 9, in which said capacitive means comprises rotatable condenser vanes having variable capacity to fixed condenser vanes on said inner conductor, and in which said header comprises an electric motor adapted to rotate said rotatable vanes and thereby cyclically modulate the frequency of the transmitter unit 20 through the required frequency sweep.
